UNITED STATES PATENT OFFICE

WILLIAM LOEFFLER, OF SHEBOYGAN, WISCONSIN

WOODWORKING MACHINE

Application filed November 8, 1929. Serial No. 405,698.

This invention relates to a new and improved return-feeder for wood working machines.

One of the objects of my invention is the provision of a machine of the above character which is adapted to be positioned in close proximity to wood working machines such as jointers and the like for receiving the work from the machine, reversing the position of the work and returning it to the machine in a very short space of time.

Another object of my invention is the provision of a return-feeder for wood working machines wherein the pieces being operated upon are received from the wood working machine, automatically turned over and returned to the wood working machine, the device including means to prevent tumbling or rolling of the pieces as their position is being reversed.

A further object of the invention is the provision of a machine of the above character wherein the operative parts thereof may be quickly and readily adjusted to accommodate material of different sizes so that regardless of the size of the material being operated upon it can be quickly and easily reversed as to its position and returned to the wood working machine.

A still further object of the invention is the provision of novel belt feeding means for the operating mechanism which reverses the position of the pieces from the wood working machine, whereby the different pieces will be readily guided from the wood working machine into the reversing mechanism and from the reversing mechanism back to the wood working machine.

A still further object of the invention is the provision of a return-feeder wherein the several parts operate consecutively so that as soon as a plank or piece of material operated upon is received onto the return-feeder it is quickly reversed and on its return movement to the wood working machine.

Another object of the invention is the provision of a return-feeder of the above character including in its construction novel means for engaging the timbers during their turning or reverse movement so as to prevent

the timbers from rolling or turning so that they will not be turned or their position reversed beyond the desired amount, said means being movably mounted so that it will readily engage and operate upon timbers of different sizes.

With the above and other objects in view, the invention consists in the novel features of construction, the combination and arrangement of parts hereinafter more fully set forth, pointed out in the claims and shown in the accompanying drawings wherein:

Figure 1 is a top plan view of a return-feeder constructed in accordance with my invention;

Figure 2 is a side elevation;

Figure 3 is a front elevation with parts broken away to illustrate the reversing mechanism, the feed and return belts for the work with their supporting structure being removed;

Figure 4 is a plan view of the arrangement of the shafts and their connections;

Figure 5 is a detail section illustrating the release mechanism in its first step;

Figure 6 is a view similar to Figure 5, illustrating the second step;

Figure 7 is an enlarged detail elevation with parts in section illustrating the step similar to Figure 5;

Figure 8 is a detail sectional view at right angles to Figure 6;

Figure 9 is a detail sectional view illustrating another step in the operation;

Figure 10 is a detail section at right angles to Figure 5, showing the release mechanism in a similar position;

Figure 11 is a sectional view on the line 11-11 of Figure 2, illustrating one step in the operation;

Figure 12 is a view similar to Figure 11, illustrating a step following that shown in Figure 11;

Figure 13 is a detail section illustrating the releasing and operating mechanism for the positioning arms;

Figure 14 is a detail longitudinal section of the means which releases the clutch for operating the mechanism shown in Figure 13;

Figure 15 is an elevation of one face of one of the clutch members;

Figure 16 is an elevation illustrating one face of the other clutch member which cooperates with the members shown in Figure 15;

Figure 17 is a detail side elevation of the timber engaging arm which engages the timber to assist in reversing its position, illustrating the arm in one position;

Figure 18 is a view similar to Figure 17, illustrating the timber engaging arm in another position;

Figure 19 is a view illustrating another position of the arm with the contact member engaging the timber to prevent rolling or turning of the same; and,

Figure 20 is an enlarged view of the return belt illustrating a timber in position about to be returned to the jointer or other wood working machine.

In the construction of my return-feeder, I provide a plurality of supporting legs 1, upon which is mounted a suitable table-like platform 2 provided at one side with an ²⁵ ⁷⁰ ⁷⁵ ⁸⁰ ⁸⁵ ⁹⁰ ⁹⁵ ¹⁰⁰ ¹⁰⁵ ⁴⁸⁸⁵ ⁴⁸⁹⁰ ⁴⁸⁹⁵ ⁴⁹⁰⁰ ⁴⁹⁰⁵ ⁴⁹¹⁰ ⁴⁹¹⁵ ⁴⁹²⁰ ⁴⁹²⁵ ⁴⁹³⁰ ⁴⁹³⁵ ⁴⁹⁴⁰ ⁴⁹⁴⁵ ⁴⁹⁵⁰ ⁴⁹⁵⁵ ⁴⁹⁶⁰ ⁴⁹⁶⁵ ⁴⁹⁷⁰ ⁴⁹⁷⁵ ⁴⁹⁸⁰ ⁴⁹⁸⁵ ⁴⁹⁹⁰ ⁴⁹⁹⁵ ⁵⁰⁰⁰ ⁵⁰⁰⁵ ⁵⁰¹⁰ ⁵⁰¹⁵ ⁵⁰²⁰ ⁵⁰²⁵ ⁵⁰³⁰ ⁵⁰³⁵ ⁵⁰⁴⁰ ⁵⁰⁴⁵ ⁵⁰⁵⁰ ⁵⁰⁵⁵ ⁵⁰⁶⁰ ⁵⁰⁶⁵ ⁵⁰⁷⁰ ⁵⁰⁷⁵ ⁵⁰⁸⁰ ⁵⁰⁸⁵ ⁵⁰⁹⁰ ⁵⁰⁹⁵ ⁵¹⁰⁰ ⁵¹⁰⁵ ⁵¹¹⁰ ⁵¹¹⁵ ⁵¹²⁰ ⁵¹²⁵ ⁵¹³⁰ ⁵¹³⁵ ⁵¹⁴⁰ ⁵¹⁴⁵ ⁵¹⁵⁰ ⁵¹⁵⁵ ⁵¹⁶⁰ ⁵¹⁶⁵ ⁵¹⁷⁰ ⁵¹⁷⁵ ⁵¹⁸⁰ ⁵¹⁸⁵ ⁵¹⁹⁰ ⁵¹⁹⁵ ⁵²⁰⁰ ⁵²⁰⁵ ⁵²¹⁰ ⁵²¹⁵ ⁵²²⁰ ⁵²²⁵ ⁵²³⁰ ⁵²³⁵ ⁵²⁴⁰ ⁵²⁴⁵ ⁵²⁵⁰ ⁵²⁵⁵ ⁵²⁶⁰ ⁵²⁶⁵ ⁵²⁷⁰ ⁵²⁷⁵ ⁵²⁸⁰ ⁵²⁸⁵ ⁵²⁹⁰ ⁵²⁹⁵ ⁵³⁰⁰ ⁵³⁰⁵ ⁵³¹⁰ ⁵³¹⁵ ⁵³²⁰ ⁵³²⁵ ⁵³³⁰ ⁵³³⁵ ⁵³⁴⁰ ⁵³⁴⁵ ⁵³⁵⁰ ⁵³⁵⁵ ⁵³⁶⁰ ⁵³⁶⁵ ⁵³⁷⁰ ⁵³⁷⁵ ⁵³⁸⁰ ⁵³⁸⁵ ⁵³⁹⁰ ⁵³⁹⁵ ⁵⁴⁰⁰ ⁵⁴⁰⁵ ⁵⁴¹⁰ ⁵⁴¹⁵ ⁵⁴²⁰ ⁵⁴²⁵ ⁵⁴³⁰ ⁵⁴³⁵ ⁵⁴⁴⁰ ⁵⁴⁴⁵ ⁵⁴⁵⁰ ⁵⁴⁵⁵ ⁵⁴⁶⁰ ⁵⁴⁶⁵ ⁵⁴⁷⁰ ⁵⁴⁷⁵ ⁵⁴⁸⁰ ⁵⁴⁸⁵ ⁵⁴⁹⁰ ⁵⁴⁹⁵ ⁵⁵⁰⁰ ⁵⁵⁰⁵ ⁵⁵¹⁰ ⁵⁵¹⁵ ⁵⁵²⁰ ⁵⁵²⁵ ⁵⁵³⁰ ⁵⁵³⁵ ⁵⁵⁴⁰ ⁵⁵⁴⁵ ⁵⁵⁵⁰ ⁵⁵⁵⁵ ⁵⁵⁶⁰ ⁵⁵⁶⁵ ⁵⁵⁷⁰ ⁵⁵⁷⁵ ⁵⁵⁸⁰ ⁵⁵⁸⁵ ⁵⁵⁹⁰ ⁵⁵⁹⁵ ⁵⁶⁰⁰ ⁵⁶⁰⁵

ings, and tightener being of the same construction as the first set.

As the piece of timber is fed inwardly by the movable belts 40, at one side of the machine, as indicated in Figure 1, the timbers will be directed between suitable guides 46 at one side of the table. At the front end of the guides 46, I mount two opposed contact rollers 47 and 48. The contact roller 47 is mounted within an upstanding U-shaped bracket 49 carried by the table 1 and within the bracket is a shaft 50 extending vertically through the bracket and through the roller 47. The lower end of this shaft carries a bevel gear 51, meshing with a similar gear 52 on shaft 53. On the inner end of shaft 53 is a sprocket 55' operatively connected with a sprocket on shaft 10 whereby a continuous rotation is imparted to roller 47 through the connection of shaft 10 with drive shaft 6.

The bracket 56 which supports roller 48 also carries a shaft 50' having on its lower end a bevel gear 51' adapted to mesh with a similar gear 52' on shaft 53' which lies parallel with shaft 53. Shaft 53' is provided with a sprocket 57 on its forward end operatively connected with a sprocket 58 on the forward end of shaft 53 whereby the two rollers 47 and 48 will be rotated simultaneously.

The supporting bracket 56 for roller 48 is mounted upon an inverted U-shaped supporting element 59 which is rockably mounted upon shaft 53' as is clearly illustrated in Figure 7. The bearing for one end of the element 59 has an arm 60 depending downwardly therethrough. The arm 60 has a laterally extension 61 carrying and engaging flange 62. Extending through the lateral extension 61 is a rod 63 supported within a stationary bracket 64 depending from the frame work of the table top.

Normally, the arm 60 is urged outwardly from the bracket 64 so that the roller 48 is normally maintained in an inclined position, as shown in Figure 3, and this arm is retained in a normal operative position by means of a coil spring 65 mounted upon rod 63 and adjusted between the bracket 64 and flanged extension 61.

However, when a piece of timber passes between rollers 47 and 48 and moves roller 48 outwardly to a substantially vertical position, arm 60 is moved inwardly against the tension of spring 65, engaging flange 62 with a hooked member 66, which extends laterally from pivoted arm 67. The arm 67 is loosely mounted upon rod 68 carried by bracket 64 and normally urged inwardly toward the bracket by means of a coil spring 69 which is disposed between the arm 67 and washer 70 on rod 68.

Arm 67 is provided upon its inner face with a cut away portion 71, the upper edge of said cut away portion having an inclined shoulder 72. It will be noted that the opening

through arm 67 which receives rod 68 is rounded or cut out at each side of the arm, as shown in Figure 10, whereby the arm can not only be rocked upon its pivot but tilted, as shown in Figure 8.

Pivotedly mounted upon the lower end of the bracket 64 is a bar 73, the forward end of which is provided with a tapering notch 74 forming a head portion 75 with an inclined face adapted to cooperate with the inclined shoulder 72 on arm 67. The forward end of the bar 73 is adapted for engagement within the cut away part 71, as shown in Figures 5 and 10.

The inner end of bar 73 is disposed beneath arm 19, as shown in Figures 4 and 12, and upon pivoted movement of bar 73 through an operation that will be hereinafter more fully described, arm 19 is raised to release sleeve 15 for engaging clutch section 16 with the clutch section 13.

It will be apparent from the foregoing that when the roller 48 is engaged by a timber, it will be forced outwardly with respect to the roller 47 moving the depending arm 60 inwardly until the flange 62 is positioned behind hook member 66. This movement placing spring 65 under tension, as shown in Figure 5.

However, as soon as the timber passes roller 48, the same will spring back to its normally inclined position due to the tension of spring 65. When the roller returns to its normal position, member 60 will move outwardly from the bracket 64 tilting arm 67 to the position shown in Figure 7. This immediately releases bar 73 and allows the forward end thereof to drop downwardly to the position shown in Figure 7. This pivotal movement of the bar 73 is urged upwardly by coil spring 76 connected to the bar 73 and the bracket 64.

As the rear end of the bar 73 moves upwardly, it engages arm 19, raising arm 19 to the dotted line position shown in Figure 11, disengaging the arm from the stud 20 allowing the sleeve 15 to move longitudinally on shaft 14, through the tension of spring 17, until the clutch section 16 engages the clutch section 13, thus imparting a rotative movement to shaft 14.

It will be noted that sleeve 15 has a finger 77 projecting therefrom adjacent the stud 20 and this finger engages a substantially U-shaped member 78 carried by the outer end of a pivoted arm 79. This arm 79 is pivoted on the depending arm 21 of bracket 22 and is normally maintained in a raised position by means of a coil spring 80, one end of which is connected to arm 79 and the other end connected to bracket 22. When the finger 77 engages with the U-shaped member 78, it will exert a downward pull on the arm 79 to the position shown in Figure 12, and as the arm 79 moves downwardly, it will engage bar 73,

as shown in Figure 9, rocking the bar 73 upon its pivot against the tension of spring 76.

- As soon as the bar 73 begins to rock upon its pivot, the forward end thereof will move upwardly and engage within the cut away part 71 with the inclined forward wall of the notch 74 on bar 73 cooperating with shoulder 72 to rock the arm 67 upon its pivot and against the tension of spring 72' disengaging hook 66 from flange 62, the spring 69 now forces arm 67 toward bracket 64 to engage bar 73 with hook or shoulder 71' on arm 67 so that bar 73 remains in locked position engaged with shoulder 71', holding bar 73 downward on the forward end and against the tension of spring 76. Flange 66 on arm 67 is now in contact with shoulder 62 on arm 60 because of the room between the shoulder 72 and the incline on the forward end of bar 73. As soon as arm 60 moves inwardly towards bracket 64, the tension of spring 72' will rock the arm 67 forward and hook 66 over flange 62 so when the arm 60 again moves outward, it will again disengage the bar 73 and it is then again in position to function as described.

- It will be apparent from the foregoing, that each time a timber has passed between rollers 47 and 48 and been positioned between the guides 46, one revolution will have been imparted to shaft 14. It will be noted that during the revolution of the shaft 14, the stud 20 will move into engagement with the cam face 25 of arm 19 and disengage the clutch face, it being apparent that as soon as bar 73 is moved downwardly by arm 79, the arm 19 will drop back in its operative position, shown in Figures 11 and 12, thus the cam face 25 may be readily engaged for disconnecting the clutch faces and as the reduced end of arm 19 is disposed within guide 24, the sleeve 15 will be positively moved upon shaft 14.

- In order that the timbers may be moved upwardly between the guides 46 so that they will be deposited upon the inclined supporting element 81, I provide novel raising means which includes a shaft 82 supported in suitable bearings 83 and carrying a plurality of sprockets 84. An idler shaft 85 is supported above in adjustable tighteners and in parallel relation with shaft 82, as shown in Figures 2 and 3. The idler shaft 85 also carries a plurality of sprockets 84' which are operatively connected with sprockets 84 by means of the chains 86. At spaced intervals, the chains carry suitable hook-like arms on flights 87 which are normally positioned at the lower edge of the guides 46 ready to engage the lower edge of a timber between the guides so that as soon as the shaft 14 moves one revolution, the two shafts 82 and 85 will be simultaneously rotated moving one of the arms 87 from the lowermost position upwardly to the top of the guides, carrying the timber to the

top of the guides where it will engage the pivotally mounted retaining arm 88 and drop downwardly onto the inclined supporting platform 81.

The shafts 82 and 85 are operated simultaneously from shaft 14 by forming operative connection between sprocket 89 on shaft 14 and sprocket 90 on shaft 82, thus operatively connecting the shafts 14 and 82 whereby simultaneous movement will be imparted to all three shafts.

The arm 88 is pivotally mounted upon a vertical slidable bar 91 and the inclined position of arm 88 is adjusted by means of the threaded rod 92, threaded through a perforated ear 93 on the upper end of the arm. The lower end of the arm 88 is preferably provided with a weight 94 to normally urge this arm to a downward position or to a normally inclined position as clearly shown in Figures 3 and 19. The particular purpose for this arm is to prevent the timbers from rolling or tumbling as they are deposited upon the inclined platform 81. It will be apparent that if it were not for this arm, some of the timbers which might be substantially rectangular in shape would have a tendency to roll or tumble when deposited on the inclined platform and would not be returned to the jointer machine in the proper position.

In order to assist the timbers in being deposited upon the inclined platform 81, I provide the upwardly extending bracket 95 upon which is pivotally mounted the rockable arm 96. The lower end of this arm 96 is formed with a cam face 97 and above the cam face is the curved recess 98 with a rounded shoulder 99 just above the recess. It will be noted that the upper end of arm 96 is yieldably connected to a lateral extension on bracket 95 by means of a coil spring 100. This coil spring normally urges the cam face 97 into position between the guides 46 where it is to be engaged by a timber passing upwardly through the guides. The relative position of the cam face 97 is controlled by means of an adjustable bolt 101, engaging the upper end of arm 96.

From the above, it will be apparent that as a timber is moved upwardly between the guides 46, it will engage the cam face 97 moving the lower end of arm 96 laterally until the timber has passed upwardly beyond the extended point 102, and thence engages the rounded shoulder 99, causing the upper edge of the timber to be guided laterally onto the inclined platform 81, and as soon as the upper edge of the timber moves away from the shoulder 99, the lower end of arm 96, through the tension of spring 100 will return to its normal position causing the lower edge of the timber to ride upwardly into the curved portion 98 and to be moved to the position, shown by the full lines in Figure 19, the dotted line position of the timber illustrating

the proper position it will assume on the inclined platform 81.

In the case of small timbers, and particularly small rectangular timbers, the upper edge thereof will not engage the rounded shoulder 99, but the lower edge thereof will ride upwardly toward the curved portion 98, as illustrated in Figures 17 and 18, and the tilting action will be completed, as shown in Figure 19.

As soon as the timber has been properly positioned upon the inclined platform 81, it will slide downwardly upon the platform through the medium of its own weight and due to the inclination of the platform it will engage the vertically positioned guide board 103, supported upon the table top at one side thereof and adjustably mounted by means of the lateral extensions 104 connected to the table top by means of the bolts 105. Movable beneath the vertical guide board 103, is the return belt 106 operating over pulleys 107 and 108, the pulley 107 being mounted upon the shaft 109 in suitable bearings 110 at the outer end of the table, while pulley 108 is mounted upon shaft 111, supported in suitable bearings 112, at the front of the table.

The shaft 111 has upon its outer end a sprocket 113 operatively connected to sprocket 30 on shaft 28 whereby shaft 111 is continuously rotated to impart movement to belt 106. As soon as the timbers have engaged the guide board 103, pivoted arms 114 normally positioned within slots 115 in the platform 81 are moved upwardly to a vertical position, as shown by the dotted lines in Figure 3, properly positioning the timber upon belt 106 so that it may be readily returned to the jointer machine through the second set of belts 40.

The operation for imparting movement to the swinging arms 114 at the proper time for correctly positioning the timber upon the belt 106 will now be more fully described. It will be noted that the forward end of shaft 14 carries a collar 116 having a cam lug 117 adapted to engage the cam surface 118 on pivoted arm 119. This arm 119 is provided with a recess portion adjacent its outer end forming an upright shoulder adapted to cooperate with the cam lug 117, as shown in Figure 3. The end of the arm 119 opposite the cam face 118, is provided with lateral extension 120 normally positioned for engagement by a finger 121 carried by a frictional clutch member 122. This frictional clutch 122 is formed in two separate parts, with one part being formed with a plurality of recesses 123 adapted to be engaged by oppositely disposed studs 124 on the other part of the clutch whereby the two parts may be readily adjusted in order to properly position the fingers 121 and 125, a finger being carried by each separable part of the clutch member.

The clutch member 122 includes the main clutch element 122, and the movable clutch element 122', both being mounted upon shaft 126 with clutch element 122' keyed to and rotating with the shaft, while the main clutch element 122 remains stationary and held in this position through the engagement of arm 119 with finger 121.

The element 122' carries a friction disc 127 adapted to cooperate with one face of the element 122 for rotating the same when the arm 119 is released from finger 121. The clutch faces are normally maintained in contact by means of a coil spring 128 mounted on a shaft 126 and disposed between collar 129 and clutch element 122. It will thus be apparent that upon each rotation of shaft 14, cam lug 117 will be rotated, engage cam face 118, moving the left end of the bar 119, as shown in Figure 3, downwardly, disengaging lateral extensions 120 from finger 121, allowing the clutch member 122 to rotate with part 122'. During the rotation of the clutch member, the fingers 125 engage the forward end of pivoted bar 130. This bar 130 is pivotally mounted upon a standard 131 on a suitable bracket 132 carried by the main frame work of the machine.

The arms 114 are all mounted upon a longitudinal shaft 133 and at the forward end of the shaft is attached a crank arm 134 connected to the vertical movable link 135. The lower end of link 135 is pivotally connected to a plunger 136 mounted in a cylinder 137. The plunger is provided with a collar 138 and adjusted between the collar and the inner end of the cylinder is a coil spring 139 which normally reduces the plunger 136 downwardly so as to normally maintain the arms 114 in an inclined position, as shown in Figure 3.

The lower end of the plunger 136 carries a roller 140 cooperating with a cam 141 carried by shaft 142 and arranged adjacent one side of a clutch section 143. The cam 141 and clutch section 143 are keyed and rotate therewith, while clutch section 144 and pinion 145 are carried by a sleeve 146 loosely mounted on shaft 142.

This pinion 145 meshes with a pinion 147 on shaft 28, so that clutch section 144 is always rotating and ready to be engaged by clutch section 143 at the proper time. Keyed to the shaft with the cam 141 is a collar 148 carrying a pin 149. Collar 148, cam 141 and clutch section 143 are slidably mounted upon the shaft 142 and are normally urged toward clutch section 144 by means of a coil spring 150 disposed between the bearing collar 151 for the shaft 142 and the collar 148. From this description, it will be apparent that when finger 125 engages the forward end of bar 130 and raises the same, it will release pin 149 and through the tension of spring 150, the clutch section 143 will be urged into en-

gagement with clutch section 144, rotating shaft 142 for one complete revolution, and during this rotative movement of shaft 142, cam 141 will engage roller 140 reciprocating plunger 136 for rocking shaft 133, which in turn will actuate arms 114 and move them to a vertical position, as illustrated by the dotted lines in Figure 3.

As soon as finger 125 has moved sufficiently to be disengaged from bar 130, the bar will drop downwardly and as this bar carries a cam face 152 on member 153 carried by the arm, the pin 149 will engage this cam face, sliding the clutch section 143 on shaft 142 away from clutch section 144 and against the tension of spring 150. As soon as the shaft 142 has completed one revolution, cam 141 will be disengaged from roller 140 allowing plunger 136 to be moved downwardly through the tension of spring 139, returning arms 114 to their normal position, as shown in Figure 3.

In moving these arms 114 upwardly to properly position the timber on belt 106, it will be understood that these arms are only retained in position a very short space of time, and this time will be sufficient to cause the forward end of the timber to be moved behind the guide member 46A at the front of the inclined platform 81 so that as soon as the timber is engaged between the guide member 46A and the vertical guide board 103, the timber can be readily guided back through the second set of belts 40 and be directed on its return to the jointer machine.

As will be noted in Figures 3 and 4, shaft 126 has mounted upon its outer end a sprocket 153 which is operatively connected with sprocket 31 upon shaft 28 whereby simultaneous movement will be imparted to shaft 126 with shaft 28 so that clutch member 122 can be operated at any time.

In order to securely retain arm 119 against lateral movement when engaged by finger 121, a stop plate 154 is attached to the bearing 155 for cylinder 137, and this stop plate 154 projects downwardly from the bearing 155 and guides arm 119 in its movement.

It will be apparent that in constructing and mounting the various parts of this machine, the parts, where found necessary, may be mounted for adjustment in accordance with the requirements. One of the essential parts which it is desired to have adjustably mounted is the bracket 56 which supports shaft 50' and roller 48. This bracket is mounted on shaft 53' and shaft 53' is mounted in slidable bearings 156 on the table and connected to the bearings is a screw member 157 adjustable in a stationary bracket 158 carried by the table top, and the screw 157 is operated by means of a hand wheel 159 whereby the roller 48 may be readily adjusted toward and away from roller 47 in accordance with the thickness of the timbers being passed

through the machine. It will be readily apparent that when comparatively thin boards or timbers are to be passed through the rollers 47 and 48, the bearings 156 can be adjusted inwardly, but if the timbers are comparatively thick, it will be essential that the bearings 156 be moved outwardly so as to accommodate the size of timbers between the rollers.

The slidable bar 91 which carries the retaining arm 88 is formed with a longitudinal slot 160 and the upright wall 3 has engaged therewith a headed bolt 161 which is positioned within the slot 160 whereby the arm 91 may be vertically adjusted to position the retaining arm 88 in accordance with the size of timbers to be deposited upon the inclined platform 81.

Another feature of this machine is the fact that regardless of the width of the boards or timbers being raised upwardly to be tilted and moved to a reverse position, is the fact that when wide boards are passed through the machine, the boards when being raised upwardly to be deposited on the inclined platform 81 will strike against the pivoted finger 162, and when wide boards are being passed through the machine, retaining arm 88 is forced upwardly raising 94 to a vertical position, which will return through its own weight to normal position after the timber has passed same, the boards or timbers readily passing upwardly and engaging the finger 162 which is normally maintained in an inclined position over the guides 46, by means of a flat spring 163 which is connected to a standard 164 on the table top and bears against the outer face of the finger to normally urge the same inwardly, as shown in Figure 3. Thus, when a board is moved upwardly, the upper edge thereof will engage this finger and be readily guided to a tilting position.

It will be apparent from the foregoing that I have provided a machine of the character set forth, which can be readily used in connection with mill working machines, such as jointer machines and the like, wherein it is necessary to pass the timbers through the jointer machine and then reverse the position of the timbers and return them to the machine for further operation. The timbers from the jointer machine will first pass through the left hand side of guide belts at the upper side of Figure 1, and thence in the rollers 47 and 48, passing through these rollers into the guides 46 formed by the upstanding wall 3 and the inner edge of the inclined platform 81. This operation, however, may be reversed if found desirable. As soon as the timbers pass rollers 47 and 48, shaft 14 is given a single revolution as previously described, moving the timbers upwardly and positioning them on the inclined platform 81. After the timbers have moved down-

wardly over platform 81 onto the return belt 106, the mechanism disclosed in Figure 13 will have passed through an operation, moving arms 114 upwardly to a vertical position, so that the timber will be held in proper position to pass through guides 46A and to be returned by the lower side of belts 40 in Figure 1, to the jointer machine.

It will be apparent from the foregoing that in the operation of my improved machine, the operation of the various parts follows successively one upon the other so that a board or other timber can be quickly received in the machine, its position reversed and the timber quickly returned to the jointer or other mill working machines, and the parts are so constructed and arranged and apparently connected so that the operations will quickly follow one another.

285 I claim:

1. In a machine of the class described including work receiving passageways, means for conveying the work through said passageways, elevating means operative in one of said passageways for raising the work therein, means operated by the movement of the work in said latter passageway for controlling the raising means, an inclined wall upon which the work is discharged when raised in the first passageway and conveyed to the other passageway and means for correctly positioning the work in the second passageway.

2. A machine of the class described including work receiving passageways, means for conveying the work through said passageways, means for elevating the work when received in one of said passageways, an inclined wall adjacent the latter passageway, means for guiding the work onto the inclined wall when elevated in the first passageway for conveying the work to the second passageway and means for straightening the work when received in the second passageway.

3. A machine of the class described including work receiving passageways, spaced rollers at one end of one of said passageways, means for rockably mounting one of said rollers, means controlled by the movement of the rockably mounted roller for discharging the work from the latter passageway after the work has passed the rollers and been received within the passageway, means for guiding the work to the second passageway and means for returning the work through the second passageway.

4. A machine of the class described including spaced work receiving passageways, spaced rollers at one end of one of the passageways, means for rockably mounting one of said rollers and normally maintaining the same in an inclined position, whereby the work passing through said rollers will move the rockable roller to a substantially vertical position, means having operative connection

with said rockable roller and adapted to be actuated through the movement of the rockable roller to its normal position after the work has passed the same and entered the passageway for moving the work upwardly 70 in the passageway, guiding means for guiding the work to the other passageway and means for moving the work through the other passageway.

5. A machine of the class described including work receiving passageways, a rockable and a stationary guide roller arranged in opposed relation at one end of one of said passageways through which the work passes, means controlled by the movement of the 80 rockable roller for raising the work in the first passageway after the work has passed said rockable roller, means for guiding the work to the second passageway, and means for moving the work through the second passageway. 85

6. A work receiving passageway, a stationary guide roller at one end thereof, a rockable guide roller in opposed relation to the stationary guide roller and normally inclining toward the first roller, normally inoperative means for raising the work in said passageway, means for retaining said raising means against movement, means actuated to the movement of the rockable roller to a vertical position when engaged by the work for releasing said raising means, and means for setting the raising means in motion through the movement of the rockable roller toward a normal position after the work has 100 been received in the passageway, a work discharge passageway, and means for guiding the work to the discharge passageway when discharged from the receiving passageway. 95

7. A return work feeder for woodworking machines comprising a longitudinally extending work-feeding device for receiving the work from the woodworking machine, an elevating device for the work located in rear of the work-feeding device, means automatically setting said elevating device in operation upon release of the work from the work feeding means, a downwardly inclined wall leading from the upper end of the elevating device, means arranged in the path of the 110 work being elevated for turning and depositing the work on the inclined wall, means engaging the work on the inclined wall for preventing tumbling of the work on said inclined wall, and return means receiving the 120 work from the inclined wall for feeding the same toward the woodworking machines. 115

8. A return work feeder for woodworking machines comprising a longitudinally extending work-feeding means receiving the 125 work from the woodworking machines, an elevating device for the work located in rear of the work-feeding means, means automatically setting said elevating device in operation upon release of the work from the feed- 130

ing means, a downwardly inclined wall leading from the upper end of the work elevating means, means arranged in the path of the work being elevated for turning and depositing the work on the inclined wall, weighted arms rockably mounted above the inclined wall for engaging the work deposited to prevent tumbling of said work sliding down the inclined wall, and return means receiving the work from the inclined wall for feeding the same toward the woodworking machine.

9. A return work feeder for woodworking machines including work receiving passageways, spaced rollers at one end of one of said passageways, means for rockably mounting one of said rollers, means controlled by the movement of the rockably mounted roller for discharging the work from the latter passageway after the work has passed the rollers and been received within the passageway, said last mentioned means including a normally inoperative drive clutch, means for guiding the work to the second passageway, and means for returning the work through the second passageway.

10. A return work feeder for woodworking machines including work receiving passageways, means for conveying work through said passageways, elevating means operative in one of said passageways for elevating the work therein, means operated by the movement of the work in said latter passageway for turning the elevating means, an inclined wall upon which the work is discharged when raised in the first passageway, and means for correctly positioning the work in the second passageway, said last mentioned means embodying swinging arms normally arranged flush with the surface of the inclined wall, means for automatically swinging said arms to an upright position when the work reaches the lower end of the inclined wall and in said second passageway.

45 11. A return work feeder for woodworking machines comprising work receiving passageways, means for conveying the work through said passageways, means for elevating the work when received in one of said passageways, an inclined wall adjacent to the latter passageway, means for guiding the work onto the inclined wall when elevated in the first passageway for conveying the work to the second passageway, said guide means including pivoted spring-pressed arms having guide noses normally disposed in the path of the work being elevated, said guide noses having upper and lower oppositely inclined guide faces for engaging the work.

60 12. A return work feeder for woodworking machines comprising spaced work receiving passageways, spaced rollers at one end of one of the passageways, means for rockably mounting one of said rollers and normally maintaining the same in an in-

clined position whereby the work passing through said rollers will move the rockable rocker to a substantially vertical position, elevating chains for the work arranged in rear of the receiving passageways and said rollers, and means having operative connection with said rockable roller and actuated through the movement of the rockable roller to its normal position after the work has passed the same and entered the passageway for setting the elevating chains in operation including a normally inoperative drive clutch, guide means for guiding the work to the other passageway, and means for moving the work through the other passageway.

In testimony that I claim the foregoing I have hereunto set my hand at Sheboygan, in the county of Sheboygan and State of Wisconsin.

WILLIAM LOEFFLER.
